(57) **CLAIM**

The ornamental design for a jewelry layout tray, as shown and described.

DESCRIPTION

FIG. 1 is a perspective view of a jewelry layout tray according to the present invention;

FIG. 2 is a top plan view thereof;

FIG. 3 is a bottom plan view thereof;

FIG. 4 is a front side elevation view thereof;

FIG. 5 is a rear side elevation view thereof;

FIG. 6 is a right side elevation view thereof; and,

FIG. 7 is a left side elevation view thereof.

The broken lines are for the purpose of illustrating the environment of the article only and form no part of the claimed design.
